UNITED STATES PATENT OFFICE.

GEORGE F. PULLEN, OF WATERBURY, CONNECTICUT, ASSIGNOR TO WATERBURY FASTENER COMPANY, OF WATERBURY, CONNECTICUT, A CORPORATION OF CONNECTICUT.

SNAP-FASTENER TOP.

1,426,100.

Specification of Letters Patent. Patented Aug. 15, 1922.

Application filed March 8, 1922. Serial No. 542,013.

To all whom it may concern:

Be it known that I, GEORGE F. PULLEN, a citizen of the United States, and a resident of Waterbury, county of New Haven, and 5 State of Connecticut, have invented certain new and useful Improvements in Snap-Fastener Tops, of which the following is a specification.

This invention relates to separable snap 10 fasteners and more particularly to a snap fastener top having a cover of celluloid or other thermoplastic material.

One object of this invention is to provide a snap fastener top of the above character 15 which will be so constructed that the celluloid shell will be positively prevented from turning relative to the collet.

A further object is to provide a snap fastener top of the above nature in which the 20 collet is provided with an outer vertical flange having serrations adapted when in use to be embedded in the celluloid shell.

With these and other objects in view, there has been illustrated in the accompanying 25 drawing, one form in which the invention may be conveniently embodied in practice.

Fig. 1 represents a plan view of the snap fastener top.

30 Fig. 2 is a top plan view of the collet member shown in detached position.

Fig. 3 is a sectional view of the snap fastener top taken along the line 3—3 of Fig. 1, looking in the direction of the 35 arrows.

Fig. 4 is a plan view of the metal blank from which the collet is formed.

Fig. 5 is a perspective view of the partly 40 finished collet, showing its appearance after the upstanding flange has been formed on the outer edge of the metal blank.

Fig. 6 is a perspective view of the collet in the next stage of its manufacture, showing its appearance after the central portion of the blank has been cupped.

Fig. 7 is a rear perspective view of the collet in its final condition—after the central flange and aperture have been formed therein.

50 In previous forms of snap fastener tops in which flexible shells, such as celluloid, were employed, there has always been a

tendency for the shells to become loosened on their supports, causing the emblems, designs, or other indicia formed on the shells 55 to twist out of their normal or "right-side up" position.

By means of the present invention, an improved form of collet has been provided whereby the shell will be positively held 60 "right-side up," and cannot twist about to an unreadable or inartistic position.

Referring now to the drawing in which like reference numerals denote corresponding parts throughout the several views, 10 65 represents a cap-disc or blank which serves as a support for the upper portion of the shell. The blank 10 is cupped slightly and has its convex side disposed upwardly. The rim, or lower edge, of the cupped blank 10 70 rests upon the flat outer rim of a spreader 11. The spreader 11, which serves to spread the eyelet and also to space the blank 10 from the collet and thereby give the desired thickness to the snap fastener top, 75 has a central aperture 12 surrounded by an annular flange 13. The annular flange 13 is formed in the shape of a truncated cone and extends downwardly into an upturned interior flange 14 of a collet 15. 80

Immediately surrounding the inner flange 14, the collet is provided with a horizontal bottom annular portion 16, terminating in an upturned intermediate vertical annular flange 17. The intermediate vertical flange 85 17 is connected at 18 to an outer vertical flange 19.

The flange 19 is provided at its bottom edge 20 with a plurality of equally spaced serrations 21 throughout its circumference, 90 which serrations are adapted to be embedded in the plastic celluloid shell when the parts are assembled, as will be herein-after described.

Surrounding the blank or cap-disc 10, the spreader 11, and the collet 15, is an outer shell 22 of any suitable plastic material, preferably of celluloid. This outer shell 22 forms the outer surface of the snap fastener top and has its circumference 23 bent inwardly around the serrations 21. The circumference 23 of said shell bridges the space between the intermediate and outer flanges 17 and 19 of the collet. The shell

22 is preferably bent into shape by heating it till plastic and then molding it around the underlying parts in a die.

The method of forming the collet 15 will 5 now be described. Referring to Figs. 4 to 7, 24 represents the original circular metal stamping or blank from which the collet is formed. This blank is provided on its circumference with a plurality of equally 10 spaced serrations or projections, preferably in the form of V-shaped notches. The first step in forming the collet from the blank 24 is to press down the outer vertical flange 19 in a suitable die, producing the article 15 as shown in Fig. 5. The second operation is to stamp down a cupped portion 25 of the shape shown in Fig. 6. The final operation consists in simultaneously stamping out a 20 circular aperture in the center of the cupped portion 25, and bending up an inner flange 14.

When it is desired to assemble the snap fastener top, it will only be necessary to arrange the blank 10, the spreader 11, and the 25 collet 15 concentrically. With the parts in this position, the outer celluloid shell 22, which has preferably been previously heated to a plastic condition, is then placed concentrically upon the top of the blank 10. 30 The shell may then be bent down over the sides of the spreader and collet and forced inwardly around the outer vertical flange into contact with the interior flange 17. During the final step of assembling the device, which is preferably performed in a 35 mold, the serrations 21 of the outer flange of the collet will become firmly embedded on the inside surface of the plastic celluloid shell, and the shell and collet will be thus 40 positively locked together. In its final condition the bottom surface of the shell will preferably lie flush with the horizontal portion 16 of the collet.

It will be understood that the snap fastener top herein disclosed will be adapted 45 to a wide variety of uses, but will probably be most used in the manufacture of glove-buttons. It will also be understood that when in use, it will be snapped over the 50 usual eyelet and that a fabric or other sheet material will be held securely between said fastener top and eyelet.

Moreover, the snap fastened top embodying this invention may be made of any 55 desired size or shape and of any suitable materials. However, it is preferred to make the shell of celluloid, the cap-disc of tin, and the spreader and collet of steel.

While there has been disclosed in this application one form in which the invention may be embodied, it is to be understood that this form is shown for the purpose of illustration only, and that the invention is not to be limited to the specific disclosure but may 65 be modified and embodied in various other

forms without departing from its spirit. In short, the invention includes all the modifications and embodiments coming within the scope of the following claims.

Having thus fully described the invention, what is claimed as new, and for which it is desired to secure Letters Patent, is:

1. In a top member for a separable snap fastener, the combination with an exterior shell, of a cap-disc, a spreader, and a 75 collet, said shell enclosing said cap-disc, spreader and collet, and engaging an outer vertical flange on said collet, said flange having means for preventing rotation of the shell relative thereto.

2. In a snap-fastener top, the combination with an exterior shell, of a cap-disc, a spreader, and a collet, said collet having intermediate and outer vertical flanges, said shell extending between the intermediate 85 and outer flanges and being locked against rotation relative to said outer flange.

3. In a snap fastener top, a cap-disc, a spreader, and a collet arranged in edge contact one upon the other, said collet having 90 an exterior vertical flange, and a shell enclosing said cap-disc, spreader, and collet, said shell being in non-rotative engagement with the edge of the exterior flange.

4. In a snap fastener top, the combination with a cap-disc, of a spreader, a collet, and a shell of thermoplastic material, said collet having a series of vertical projections formed on its perimeter, said projections being embedded in said shell to positively hold said shell against turning.

5. In a snap fastener top, the combination with a cap-disc, of a spreader, a collet, and a shell of thermoplastic material, said collet having an outer vertical flange locked 105 to the edge of said shell for holding said shell against turning.

6. In a snap fastener top, the combination with a cap-disc, of a spreader, a collet, and a shell of thermoplastic material, said collet having an outer serrated vertical flange embedded in the edge of said shell for holding 110 said shell against turning.

7. In a snap fastener top, the combination with a cap-disc, of a spreader, a collet, and a shell of thermoplastic material, said collet having an outer serrated vertical flange embedded in said shell for holding 115 said shell against turning.

8. In a snap fastener top, the combination with a cap-disc, of a spreader, a collet, and a shell of thermoplastic material, said collet having an outer vertical flange engaging the edge of said shell, said flange having means for locking said shell against turning relative thereto.

9. In a top for a separable snap fastener, the combination with a cap-disc, of a spreader, a collet, and a celluloid shell, said collet having a flat base, and a U-shaped 130

annular rim connected to said base, the outer vertical edge of said U-shaped rim having a series of projections adapted to engage said celluloid shell when assembled, whereby said shell will be prevented from turning relative to said collet.

10. In a snap fastener top, a celluloid shell, a cap-disc, a collet, and a spreader located

between said cap disc and said collet, said collet having an outer vertical, notched rim 10 embedded in said celluloid shell for preventing it from turning.

In testimony whereof, I have affixed my signature to this specification.

GEORGE F. PULLEN.
